UNITED STATES PATENT OFFICE.

WILLIAM C. SMITH, OF NEW YORK, N. Y., ASSIGNOR TO NATHAN LEVY,
OF SAME PLACE.

DESIGN FOR A FRAME FOR BICYCLE-SADDLES.

SPECIFICATION forming part of Design No. 25,648, dated June 16, 1896.

Application filed March 23, 1896. Serial No. 584,554. Term of patent 7 years.

To all whom it may concern:

Be it known that I, WILLIAM C. SMITH, a citizen of the United States, residing at New York city, in the county and State of New York, have invented and produced a new and original Design for the Frames of Bicycle-Saddles, of which the following is a specification, reference being had to the accompanying drawings, forming a part thereof, which

10 shows, in—

Figure 1, a perspective view of a bicycle-saddle frame embodying the features of the design, and in Fig. 2 a plan of the same.

In general contour the saddle-frame is approximately oval, and its front portion is inclined gradually forward from the ends in direction of the transverse center of the frame, meeting at the latter point what appears as an abbreviated pommel A. The bottom B of

20 the frame is apparently dish-shaped at the

checks and is of riddled appearance. In the transverse center of the body of the frame is a pear-shaped opening C, commencing at the cantle portion of the frame and leading to the representation of the pommel, while the marginal surface of the exterior of the body of the frame, the corresponding portion of the pommel projection, together with the margin of the opening C, are correspondingly bounded by a border D, which border apparently rises ²⁵ from the body of the frame and is intended to represent a flange. ³⁰

I claim—

The design for a bicycle-saddle frame, substantially as herein shown and described.

WILLIAM C. SMITH.
